WILLIAM BURLINGHAM, OF NEWPORT NEWS, VIRGINIA, ASSIGNOR OF ONE-HALF TO
JOSEPH BRIGGS WEAVER, OF NEWPORT NEWS, VIRGINIA.

PERCUSSIVE BOILER-TUBE CLEANER.

1,134,723.

Specification of Letters Patent.

Patented Apr. 6, 1915.

Application filed August 19, 1914. Serial No. 857,434.

To all whom it may concern:

Be it known that I, WILLIAM BURLINGHAM, a citizen of the United States, residing at Newport News, county of Warwick, 5 State of Virginia, have invented a new and useful Percussive Boiler-Tube Cleaner, of which the following is a specification.

The boiler tube cleaners for tubes and flues which are at present in general use have, for the most part, consisted of reciprocating or rotary blades adapted to be inserted into the tube or flue for the purpose of cutting out the deposits, which construction has only been applicable to cylinders or tubes of comparatively large diameter. It has also been heretofore proposed to employ cylindrical brushes or brushes of analogous character insertible in a tube and rotated therein from the outside of the 10 boiler, which form can be employed in tubes of small diameter but which could not conveniently be employed with curved tubes. It has also been heretofore proposed to employ a pneumatic impact tool having cutting members loosely held by an attachment 15 from the forward end of the tool cylinder, but in this device no means such as I employ are provided for causing the scale removing devices to normally remain in close juxtaposition with each other so as to 20 permit the implement to be readily inserted into the tube or flue to be cleaned.

My present invention relates to a novel construction of a percussive boiler tube or flue cleaner, which is capable of a wide variety of uses, and wherein the disadvantages of prior devices are overcome, and consists of a novel construction of a tube or flue cleaner, wherein the pneumatic impact tool cylinder is incased for its entire 25 length in a cylinder or jacket, one end of which is securely locked into engagement with the end of the pneumatic tool cylinder, while the outer end thereof is provided 30 with the scale removing devices, said outer jacket or casing being provided with longitudinally extending cuts whereby resilient arms are provided which cause the scale 35 loosening devices to instantly assume their normal position after the impact of the hammering piston, so that the implement can be readily advanced within the tube, or flue to be cleaned, according to requirements.

To the above ends my invention consists

of a novel construction of percussive tube or flue scaling implement adapted to be worked with either compressed air, steam or other motive fluid, whereby the scale can be readily removed from the interior of the 60 tubes or flues of water tube boilers, condensers, steam economizers and the like, my invention being also adapted to remove the scale from the outside of tubes of fire tube boilers by rapid internal blows within the 65 tube, the scale not only being chipped from the interior of the tube, but also being removed from the exterior surface thereof by the vibration of my novel tool against the interior of the tube.

For the purpose of illustrating my invention, I have shown in the accompanying drawing one form thereof which is at present preferred by me since it will be found in practice to give satisfactory and 70 reliable results, although it is to be understood that the various instrumentalities of which my invention consists can be variously arranged and organized and that my invention is not limited to the precise arrangement and organization of these instrumentalities as herein shown and described.

Figure 1 represents a longitudinal section of a novel construction of a flue cleaner 85 embodying my invention. Fig. 2 represents a side view of the hammer block element of the same, in detached position. Fig. 3 represents an end view of Fig. 2.

Similar numerals of reference indicate 90 corresponding parts in the figures.

Referring to the drawings:—1 designates a cylindrical barrel or working cylinder, having an axial piston chamber consisting of a large diameter axial bore 2, and a small 95 diameter axial bore 3, said bores forming a differential piston chamber, the rear end of said large bore having a screw-threaded portion 4. An externally threaded block 5 is fitted in said threaded rear end of the piston 100 chamber and has a rearwardly extending axial neck 6, having its outer end 7 screw-threaded. The neck has an axial bore 8, at the closed inner end of which are radial 105 channels 9, which extend through the block, and are connected by an annular channel 10, in the threaded periphery of the block. A coupling 11 is secured to the end of the neck 6 and conveys motive fluid, such as air under pressure, steam or other motive fluid, from a 110

suitable reservoir or generator or other source, not shown. A differential plunger is reciprocable within the plunger chamber and has an enlarged piston 12, fitting in the large bore 2 and a smooth, smaller, cylindrical plunger portion 13, fitting to slide in the small diameter bore 3. The end of said plunger portion is formed with a conical or similar tapering head or striker 14. The 10 plunger has an axial chamber 15, open through the larger or upper face of the same and extending about one half of the length of the plunger, and the walls of said chamber preferably flare or diverge rearwardly, 15 said chamber having radial channels 16, extending outwardly through its walls. A longitudinal channel 17 is formed in the wall of the tool cylinder or barrel, and has its lower or right-hand end communicating by a 20 port 18 with the lower end of the large piston chamber and its upper or left-hand end communicating with the circumferential groove 10 of the threaded block and the radial channels therein through a port 19. 25 In Figs. 2 and 3 I have shown in detached position, views of the hammer block member 20, which comprises a cylindrical shell or jacket inclosing the pneumatic tool cylinder 1 for its entire length, said shell having 30 a head 21 at its upper or left-hand end, which has a central opening 22 therethrough, through which passes the inlet neck 6, said head being provided with a central hub 23 upon which fits a cap 24, also bearing against 35 the head and held in place by a nut 25 which is in threaded engagement with the threaded portion 7 of said inlet neck.

It is essential in the construction of the hammer block member 20, that the exterior scale removing devices be normally held substantially in juxtaposition as seen in Fig. 1, so that the implement can be readily advanced within the tool to be cleaned, and it is also essential that the scale removing devices be resiliently supported so that said scale removing devices on the forward end of the hammer block member or members will, so far as practicable, assume their normal position seen in Fig. 1 during the slight intervals when the end of the hammering piston 13 is out of contact therewith.

To the above ends, I provide the inclosing shell or jacket 20 with a plurality of longitudinal extending cuts 34, which extend for a greater part of the length of the outer shell to form spring arms 26, which normally bear against the surface of the pneumatic tool cylinder or barrel, said spring arms terminating in segmental blocks 27, which extend 55 beyond the lower or right-hand end 33 of the cylinder 1 and are constructed so that a tapering internal chamber 28 is formed, the lower or outer portion 29 of which is tapered to substantially correspond to the conical or 60 tapering head 14 of the hammering piston or

plunger, said hammer block member having an axial bore 30 at its end.

The outer faces of the hammer blocks 27 are formed with circumferential or other shaped ribs or projections 31 of any desired 75 or required cross-sectional shape, and it will be apparent that projections of any other suitable shape for chipping or cutting the scale or other deposits in the tubes may be employed. The head 21 at or near the junction of the spring arms 26 therewith may be cut away or provided with a circumferential groove 32 or otherwise equipped so as to increase or vary the resiliency or elasticity of 80 said spring arms 26, as will be evident.

In practice, in the operation of the tool, the latter is inserted into the tube to be cleaned and compressed air or other motive fluid is admitted through the inlet coupling 85 11. The fluid passes through the inlet passage 8, radiating channels 9 in the head, circumferential channel 10, port 19, and longitudinal channel 17 in the barrel, which 90 communicates with the lower end of the piston cylinder. When the plunger is in its upper or left-hand position, as seen in Fig. 1, the ports in the plunger are uncovered in the piston chambers and the fluid passes through the above-named ports and 95 the ports 18 and 16 to the axial chamber 15 of the plunger to the upper end of the piston chamber and, acting against the large upper or left-hand area of the plunger and exerting differential pressure upon such area, forces the plunger downwardly or to 100 the right of the position seen in Fig. 1. When the plunger arrives at the lower or right-hand end of its stroke, the ports are uncovered and the fluid flows out in the chamber in the lower end of the shell from 105 the chamber in the plunger and from the barrel above the same, releasing the down-pressure upon the plunger and allowing the normal pressure of the motive fluid to act upon the small-area surface of the piston 110 to again drive the plunger upward. The hammering plunger is thus reciprocated in the manner of the plunger of the valveless hammer of the old and well-known "Chouteau" type, and I deem it unnecessary to 115 describe its cycle of operation in greater detail, as I may employ any suitable type of valveless or other pneumatic hammering tool in order to obtain the desired reciprocations of the hammering piston.

The reciprocations of the plunger will cause its tapering end or striker 14 to intermittently impact against and spread the blocks 27 of the spring arms 26 to deliver sharp laterally diverging blows upon the interior of the tube and thus chip or crack the scale or other accumulated deposits within the tube to be cleaned. The exhaust from the lower end of the plunger will blow out through the cuts 34 of the hammer block 120 125 130 20

and blow the scale and detritus out of the tube to which the implement is applied. My novel construction of implement, with slight modifications, may also be employed

- 5 for expanding tubes of comparatively soft and malleable metal within tubes of cylindrical bores, the hammer blocks being shaped to strike the inner wall of the malleable tube so as to expand the latter and thus
 10 secure it in the surrounding tubular wall. By this use of the tool, an inner tin or lead pipe can be expanded within an outer iron or steel pipe to line the latter, and will be firmly secured in the surrounding contiguous
 15 tubular wall.

The spring arms may have their resiliency or elasticity varied according to requirements by reducing them in various manners besides by forming the annular groove 32
 20 illustrated, and the degree of elasticity or resiliency of the arms 26 can be varied, according to requirements.

While for the sake of simplicity, the percussion structure I have hereinbefore described is preferably of the valveless type, it is evident that a valved percussion tool or any other percussion tool imparting radiating outward blows can be employed, without departing from the spirit of my invention.

It will be seen from the foregoing that the impact of the blows of the rapidly reciprocating piston upon the plurality of internal, inclined scale removing devices will cause the same to rapidly vibrate radially, and that the provision of the spring arms 26 will cause the scale removing devices to normally assume the position seen in Figs. 1 and 2, so that the implement can be readily advanced within the straight or curved tubes or flues which it may be desired to clean. The exhaust will pass through the ports 16 at the proper intervals and will escape through the slots or cuts 34, as is evident, and the exhaust air from the implement will blow the soot from the inside of the smaller tubes to be cleaned into the stack, without requiring any attention on the part of the operator.

50 My invention is particularly adapted to the cleaning of small tubes like the one and one-eighth inch tubes on torpedo boats, which are at present usually cleaned by a wire brush which is reciprocated within the tube but brushes off the soft scale only, the hard lime deposit not being removed by these wire brushes. By my invention small tubes of the character referred to can be readily cleaned and sufficient power is created to remove the lime scale therein deposited.

I desire to call special attention to the employment of the resilient arms 26 which preferably extend the entire length of the
 65 tool cylinder 1 and inclose the same substan-

tially as described, so that the entire device when assembled presents a neat and compact appearance, and can be readily manipulated by the operator.

It will now be apparent that I have devised a new and useful percussive boiler tube cleaner which embodies the features of advantage enumerated as desirable in the statement of the invention and the above description, and while I have, in the present instance, shown and described a preferred embodiment thereof which will be found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:

1. In a percussive boiler tube cleaner, a pneumatic tool cylinder, a hammering piston therein, an outer cylinder inclosing said tool cylinder and having a plurality of resilient arms extending longitudinally of said tool cylinder, said arms substantially surrounding said tool cylinder, and scale removing devices formed on the opposite terminals of said resilient arms, the inner walls of said terminals being impacted upon by said hammering piston.

2. In a percussive boiler tube cleaner, an inner pneumatic tool cylinder, a hammering piston therein, an outer cylinder in engagement with said inner tool cylinder and having spring arms integral therewith and engaging said tool cylinder for its entire length, and hammer blocks at the free outer terminals of said spring arms adapted to be engaged and moved outwardly by the impact of said piston therewith.

3. In a tool of the character stated, an inner cylinder having a motive fluid inlet, a piston reciprocable in said cylinder and having a tapering striker thereon, an outer cylinder engaging said inner cylinder, said outer cylinder having spring arms secured thereto and engaging the outer periphery of said inner cylinder for its entire length, and hammer blocks at the free outer terminals of said spring arms adapted to be engaged and moved outwardly by the tapering portion of said piston.

4. In a tool of the character stated, an inner cylinder having a motive fluid inlet, a plunger reciprocable in said cylinder and having a tapering striker thereon, an outer cylinder having integral spring arms engaging the outer periphery of said inner cylinder for its entire length, thickened wedge-shaped hammer blocks at the free outer terminals of said spring arms, said blocks being adapted to have radial movement and formed with oblique internal sides adapted

to be engaged and radially moved by the tapering portion of said plunger.

5. In a percussive boiler tube cleaner, a pneumatic tool cylinder, a hammering piston therein, a closure for one end of said cylinder having a neck leading therefrom and provided with an inlet leading to said cylinder, a head engaging said neck, a cap 10 engaging said head, means for securing said head and cap with respect to said cylinder, spring arms projecting from said head, longitudinally of said cylinder, and hammer blocks on the ends of said spring arms, the inner walls of said hammer blocks being 15 impacted upon by said piston.

6. In a percussive boiler tube cleaner, a pneumatic tool cylinder, a hammering piston therein, a closure for one end of said

cylinder having a neck leading therefrom and provided with an inlet leading to said cylinder, a head engaging said neck and abutting against an end of said cylinder, a cap engaging said head, means for securing said head and cap with respect to said cylinder, spring arms projecting from said head longitudinally of said cylinder, an annular groove around said head near the terminal of said spring arms for imparting resiliency to the latter, and hammer blocks on the ends of said spring arms, the inner walls of said hammer blocks being impacted upon by said piston.
